(57) **CLAIM**

The ornamental design for the carton, as shown and described.

DESCRIPTION

FIG. 1 is a front perspective view of the carton according to the present invention.

FIG. 2 is a rear perspective view of the carton as shown in FIG. 1.

FIG. 3 is a front elevation view of the carton as shown in FIG. 1.

FIG. 4 is a rear elevation view of the carton as shown in FIG. 1.

FIG. 5 is a left side elevation view of the carton as shown in FIG. 1.

FIG. 6 is a right side elevation view of the carton as shown in FIG. 1.

FIG. 7 is a top plan view of the carton as shown in FIG. 1; and,

FIG. 8 is a bottom plan view of the carton as shown in FIG. 1.

The feature shown in broken lines in FIGS. 1, 2, 3, 5, 6 and 7 illustrating a pour spout and the feature shown in broken lines in FIGS. 8 depicting a seam line, represent portions of the carton that form no part of the claimed design.

The edges of the carton shown in solid lines and the area surrounded by solid line edges define the claimed design. All broken lines and the area within the curved broken lines in FIGS. 1, 2, 3 and 6 represent unclaimed environmental subject matter.
